DESIGN FOR A COMBINED PEDAL AND CRANK FOR A CYCLE

Herman L. Kraeft, Cleveland Heights, Ohio, assignor to The Murray-Ohio Manufacturing Company, Cleveland, Ohio, a corporation of Ohio

Application October 5, 1936, Serial No. 65,169

Term of patent 7 years

To all whom it may concern:

Be it known that I, Herman L. Kraeft, a citizen of the United States, residing at Cleveland Heights, in the county of Cuyahoga and State of Ohio, have invented a new, original, and ornamental Design for a Combined Pedal and Crank for a Cycle, of which the following is a specification, reference being had to the accompanying drawing, forming a part thereof.

In the drawing, Fig. 1 is a side elevation of a

combined pedal and crank for a cycle, showing my new design; Figs. 2 and 3 are respectively, a front elevation and a plan view of the combined pedal and crank, viewed as indicated on Fig. 1; Fig. 4 is a sectional view of the crank as indicated by the line 4—4 on Fig. 2.

I claim:

The ornamental design for a combined pedal and crank for a cycle, substantially as shown.

HERMAN L. KRAEFT.
